LOGGING CAR CHOCK

Matt Markkula, Fort Bragg, Calif.

Application September 26, 1936, Serial No. 102,770

8 Claims. (Cl. 105—385)

This invention relates to logging car chocks and pertains particularly to improvements in the locking mechanism for stakes or chocks of the kind disclosed in my prior Patent Number 5 1,398,441 for Stake for flat-cars, issued November 29, 1921.

In said prior patent there is disclosed a mechanism for retaining logs or the like on a flat car, and which comprises generally, pairs of stakes 10 or chocks arranged opposite each other on the bed of the car and received in transversely extending guideways having their ends offset in a downward direction, so that the chocks may be received in an unobstructing position below the log-supporting surface of the car. A locking rod is attached to each of the stakes and extends transversely of the car beneath the car bed. A chain or other suitable device is secured to the end of the locking rod and co-operates with a lock member positioned on the side of the car to retain the chock in its operative position. When the car is to be unloaded, the locking member is released and the weight of the logs moves the chock downwardly until it is received by the 25 offset ends of the guideways, so that it assumes a position permitting the logs to roll off the sides of the car.

It is with the said locking member and its related parts that the present invention is particularly concerned. In unloading logs from flat cars it is common practice to move the car past a log-dumping station which comprises a barrier known as a "log-dump" built to lie closely adjacent the edge of the moving car. The natural 30 position for the locking member of the chock is such that it is very likely to strike against the log-dump as the car passes, with the result that the lock may be released or destroyed. The accidental breakage or release of a lock upon a loaded 35 car presents a condition hazardous to workmen, and increases the cost of the logging operations.

It is the object of the present invention to provide an improved chock for logging cars which is superior in point of safety and efficiency to devices heretofore known.

Another object of the invention is the provision of a logging car chock having a locking member designed and arranged to prevent accidental breakage or unlocking thereof by contact with a log-dump or other objects past which the car may move. A further object of the invention is the provision in a logging car chock of a locking mechanism that is easily actuated to secure the chock in chocking position but having means to resist accidental unlocking of the chock. Fur-

ther objects and advantages of the invention are made apparent in the following specification, wherein reference is made to the accompanying drawing which illustrates one form which my invention may assume.

In the drawing,

Fig. 1 is an end view of a flat car positioned alongside of a log-dump and provided with chock members embodying the novel features of my invention;

Fig. 2 is an enlarged end view of one of the chock members illustrated in Fig. 1;

Fig. 3 is a sectional view taken on the line III—III of Fig. 2, with the locking mechanism removed; and

Fig. 4 is a perspective view of a portion of the locking mechanism illustrated in Fig. 2.

Referring to the drawing in detail, Fig. 1 illustrates a flat car loaded with logs and moving along tracks 10 which are inclined, to cause one edge of the car to assume the level of a log-dump 11 which extends parallel to the tracks 10 and parallel to the edge of a log-pond 13 into which the logs are dumped to be transported by floating to any desired point. The car is provided with 20 pairs of chock members generally indicated at 14, which are substantially triangular in shape and each of which comprises a body portion 15 (see Fig. 3) having a flange 16 formed on its two upstanding sides. The ends of the flange are 30 rounded as at 17 and 18 to form bearing surfaces which slide upon guides 19. The body portion of each chock is provided with an extension having a transverse member 20 arranged below the guides 19. The guides are carried by a hollow 35 casing which comprises side plates 21 and top plates 22 and a transverse brace 23, so that it may be conveniently and securely supported between transverse beams 24 (see Fig. 2) of the car. The outer ends of the guides 19 slope downwardly 40 as shown at 25, thus providing a space within which the chock 14 may be received, as illustrated at the left-hand side of Fig. 1, when it is moved toward the outer end of the car. A locking rod 27 is secured to each of the chocks and 45 extends toward the opposite side of the car within the space between the transverse beams 24 which receives the casing supporting the chock. A chain 28 forms an extension of each of the bars 27 and passes through an opening 29 in the 50 otherwise closed end of the casing.

The device as described up to this point is identical in principle with that disclosed in my prior patent referred to above, but means presently to be described, for locking and releasing 55

the chocks, constitute improvements over the disclosure of the said patent.

Referring to Figs. 1 and 3, the case which supports the chock for sliding movement upon the guides 19 is shown as having its outer end recessed or cut away at the lower corner, and a guideway 30 is provided within this recessed portion, for the reception of a chain lock generally indicated at 31, which co-operates with the chain 28 to secure the chocks in their chocking position, such position being illustrated at the right hand side of Fig. 1. Through this positioning of the locking mechanism, there is no possibility of the lock or any of its parts coming into contact with the log-dump 11 as the car passes the dump and as the chock is released to permit the logs to roll from the car over the dump and into the pond. The outer face of the casing is flush with the outer edge of the car so that a rugged structure extending the full length of the car overhangs and protects the locking mechanism.

The construction of the sliding lock member which is received in the guideway 30 is illustrated in Figs. 2 and 4. It comprises a flat plate with a longitudinally disposed slot 32 adapted to receive a horizontally disposed link of the chain 28 where it passes through the opening 29, and to prevent the passing therethrough of the chain, 30 by reason of its contact with the vertically disposed links adjoining the opposite ends of the engaged, horizontally disposed link. The slot 32 is widened toward one end of the plate and opens through the lower edge of the plate, as at 33, 35 so that upon sliding movement of the locking member in the guides 30 and in a left-hand direction as viewed in Fig. 2, the enlarged portion of the slot 32 registers with the hole 29 and permits the chain 28 to pass freely therethrough, 40 so that the weight of the logs on the car will move the released chock to its unobstructing position.

The lower edge of the lock member is provided with an ear 34 which is disposed adjacent the end of the lowermost guide member 30, when the chain is locked. The sliding member fits loosely in the guides 30, so that it may be slightly raised to cause the ear 34 to pass over the edge of the guide member when the lock is to be released. This construction resists the releasing movement of the lock and prevents accidental or premature opening thereof. A head 35 is provided on the outer end of the locking member, and this head may be struck a sharp blow with a 55 sledge-hammer or the like, to cause the ear 34 to ride into the guideway 30 and release the lock at the proper time. The head 35 comprises a rearwardly extending lug 36 which, upon movement of the plate 31 to its chain-releasing position, contacts the side of the casing to prevent the plate from sliding any farther than is necessary.

The chocks are set in their chocking position and locked at the time that the logs are loaded 65 upon the car. When the logs are to be dumped, the locking member on the opposite side of the car from which the dumping is to take place is released by striking the head 35 with a sledge or the like. The chock is then forced downwardly 70 by the weight of the logs rolling from the car, and as it moves outwardly it assumes the position illustrated at the left-hand side of Fig. 1, where the logs are permitted to roll over it with perfect freedom.

Certain features of my invention have been described in detail by way of illustration, but it should be understood that various changes may be resorted to in the construction and arrangement of its several parts, within the spirit and scope of the invention as it is defined in the appended claims.

Having described my invention, what I claim and desire to secure by Letters Patent is—

1. In a chocking device for logging cars and the like, comprising chock members adjustable transversely of the car, casings disposed at opposite edges of the car and receiving said chock members, said casings having recessed portions in their outwardly facing surfaces, and locking means for said chock members disposed within said recesses. 10

2. In a chocking device for logging cars and the like, a pair of chock members arranged at opposite sides of the car and adjustable transversely of the car, locking members disposed beneath an overhanging edge of the car, one adjacent each chock, and a connection between the chock on each side of the car and the locking member on the opposite side. 20

3. In a chocking device for logging cars which comprises adjustable chock members disposed at opposite sides of the car, a locking member adjacent each chock member for co-operation with a chain leading from the opposite chock member and comprising a slideable plate having a slot for engagement with the chain, said slot being enlarged toward one end to permit free movement of the chain therethrough. 30

4. In a chocking device for logging cars which comprises adjustable chock members disposed at opposite sides of the car, a locking member adjacent each chock member for co-operation with a chain leading from the opposite chock member and comprising a plate slideable in guideways from a position engaging said chain to a position releasing said chain, and an ear on one edge of said plate engageable with one of said guideways when the plate engages the chain to resist movement of the plate to a position releasing the chain. 40

5. In a chocking device for logging cars which comprises adjustable chock members disposed at opposite sides of the car, a locking member adjacent each chock member for co-operation with a chain leading from the opposite chock member and comprising a plate slideable in guideways from a position engaging said chain to a position releasing said chain, an ear on one edge of said plate engageable with one of said guideways when the plate engages the chain to resist movement of the plate to a position releasing the chain, and a head on one end of said plate providing a point to be struck to move the plate to a releasing position. 50

6. A chain lock for a logging car chock which comprises a plate slideable in guideways over an opening through which a length of chain passes and having a slot wide at one end and narrow at the other end to engage and release said chain upon sliding of the plate. 60

7. A chain lock for a logging car chock which comprises a plate slideable in guideways over an opening through which a length of chain passes and having a slot wide at one end and narrow at the other end to engage and release said chain upon sliding of the plate, and means on the plate engageable with the guideways to resist movement of the plate to its chain releasing position. 70

5 8. A chain lock for a logging car chock which comprises a plate slidable in guideways over an opening through which a length of chain passes and having a slot wide at one end and narrow at the other end to engage and release said chain upon sliding of the plate, means on the

plate engageable with the guideways to resist movement of the plate to its chain releasing position, and a lug on said plate to stop its movement when it attains its chain releasing position.

MATT MARKKULA.
